UNITED STATES PATENT OFFICE.

WILLIAM J. HARTNETT, OF AUSTIN, TEXAS.

MANUAL-TRAINING APPARATUS.

1,176,365.

Specification of Letters Patent. Patented Mar. 21, 1916.

Application filed April 27, 1915, Serial No. 24,199. Renewed December 24, 1915. Serial No. 68,581.

To all whom it may concern:

Be it known that I, WILLIAM J. HARTNETT, a citizen of the United States, residing at Austin, in the county of Travis and State of Texas, have invented certain new and useful Improvements in Manual-Training Apparatus, of which the following is a specification.

This invention relates to new and useful improvements in a manual training apparatus.

The object of the invention is to provide a device of the character described which is specially designed for teaching the art of swimming and may also be used as a physical exerciser generally.

With the above and other objects in view, the invention has particular relation to certain novel features of construction, operation and arrangement of parts, an example of which is given in this specification and illustrated in the accompanying drawings, wherein:

Figure 1, is a side elevation of the device in use. Fig. 2, shows an enlarged side elevation thereof, partially broken away. Fig. 3, shows an end view thereof, and, Figs. 4 to 8, inclusive, show detached views of the operating parts.

Referring now more particularly to the drawings, wherein like numerals of reference designate similar parts in each of the figures, the numeral 1, refers to the mat or body rest, composed of the frame 2, and cushion 3, and which is mounted upon the tripod formed of the front legs 4, 4, and the rear leg 5. The upper ends of the legs 4, 4, are connected by the arch 6, whose side is arcuate and sustains the front end of the frame 2, which is pivoted to the center thereof. The upper end of the leg 5, is pivoted to the rear part of the frame 2, so that the mat may have a limited lateral rocking motion and interposed between the arch 6, and frame 2, on each side, are the coil springs 7, 7, which serve as cushions and normally hold the mat level. U shaped levers 8, 8, are provided whose forward ends are pivoted to the rear end of the frame 2, on each side and the free ends of the levers have the flexible collars 9, 9, secured thereto and provided to be strapped around the ankles of the learner.

Projecting forwardly from the legs 4, 4,

and fixed thereto are the brackets 10, 10, 55 whose free ends have bearings for a purpose later to be set forth. A shaft 11, is provided which has the wrists 12, 12, to which the forward ends of the respective links 13, 13, are pivoted and the rear ends 60 of these links are pivoted to the corresponding levers 8, 8. The cranks 14, 14, are provided having inwardly turned ends which pass through the bearings of the brackets 10, 10 and are connected by universal joints 65 to the respective ends of the shaft 11, and have the grips 15, 15, by means of which the cranks and shaft 11, are rotated.

The learner should lie, face downward upon the mat with the collars 9, 9, fastened 70 around his ankles, and grasp the grips 15, 15, and turn the cranks. Motion will be imparted through the shaft 11, the links 13, 13, and the levers 8, 8, to the lower links and these body movements will be very similar 75 to the movements of the body in swimming; and by practice, one will soon become accustomed to the movements which he must make in swimming in water. The practice is also a healthful exercise in addition to 80 acquiring the ability to swim.

What I claim is:

1. A device of the character described including a body support, legs upon which the same is mounted, levers pivoted at one 85 end to the support, a shaft, wrists carried thereby, links pivoted at one end to the wrists and at the other to the levers, and means for rotating said shaft.

2. A device of the character described including a mat, supporting legs upon which the same is pivoted, so as to rock laterally, levers pivoted at one end to the mat, a shaft, wrists carried thereby, links pivoted at one end to the wrists and at the other to the 95 levers, and means for rotating said shaft.

3. A device of the character described including a mat, a support therefor, levers pivoted at one end to the mat, a shaft, wrists carried thereby, links pivoted at one end to 100 the wrists and at the other to the levers, and means for rotating said shaft.

4. A device of the character described including a mat, for supporting the body, a support upon which the mat is pivoted to 105 rock laterally, a pair of levers pivoted at one end to the mat end, collars carried by the free ends of the levers, a shaft rotatably

mounted at the other end of the mat, wrists carried thereby, links pivoted at their respective ends to said wrists and the corresponding levers and cranks connected by 5 universal joints to the respective ends of said shaft.

In testimony whereof I have signed my

name to this specification in the presence of two subscribing witnesses.

WILLIAM J. HARTNETT.
